ILLUMINATOR

Lindsley Schepmoes, New Haven, Conn., assignor
to The Safety Car Heating & Lighting Com-
pany, a corporation of New Jersey

Application March 22, 1937, Serial No. 132,226

7 Claims. (Cl. 240—7.35)

This invention relates to a lighting fixture and more particularly to a lens therefor for use in a railroad car or the like.

It is among the objects of this invention to provide an illuminating device which is inexpensive to manufacture and install, which enhances the appearance of the enclosure which it illuminates, and which efficiently illuminates the enclosure without causing undue glare therein.

10 The invention accordingly consists in the features of construction, combinations of elements, and arrangements of parts as will be exemplified in the structure to be hereinafter described and the scope of the application of which will be indicated in the following claims.

In the drawings, in which are shown several of the possible embodiments of my invention,

20 Figure 1 is a fragmentary transverse elevation of a railroad car in which my illuminator is installed;

Figure 2 is a view similar to Figure 1, except that the illuminator is installed in a different position;

25 Figure 3 is a fragmentary longitudinal elevation of the railroad car and lighting fixture shown in Figure 1;

Figure 4 is a plan view corresponding to Figure 3;

30 Figure 5 is a detailed sectional elevation of an installation of my lighting fixture;

Figure 6 is an exploded perspective of the several elements which comprise my lighting fixture;

35 Figure 7 is a perspective of a modified form of my lighting fixture;

Figure 8 is a sectional elevation of my fixture taken along the line 8—8 of Figure 7;

Figure 9 is a perspective view of another modification of my lighting fixture; and

40 Figure 10 is a sectional elevation taken along the line 10—10 of Figure 9.

Various attempts have been made in the past to illuminate effectively localized areas in an enclosure such as a railroad car or other similar carrier. The success of these attempts has been at best indifferent; installations of this general character are characterized by the creation of discomforting glare and a general atmosphere of gloominess throughout the car, especially in the upper portions thereof.

Some of the lighting fixtures now being used for localized or "spot" illumination of the normal reading plane in the car, provide either too little or too much light in the desired areas. This is usually due to the emanation of a symmetrical

beam from the light source. The use of other fixtures results in a semi-dark condition in the upper portion of the car due to a lack of light diffusion longitudinally of the car, or such fixtures diffuse so intensely in lateral directions that they create a bothersome glare. It is a further object of this invention to rectify the above conditions, in addition to others of a similar nature.

Referring now to the drawings, and particularly to Figure 1, a car 10 is provided with seats 12, over which extends a baggage rack 13 having secured thereto a lighting fixture generally indicated at 14. Seats 12 are preferably pivotally mounted on pedestals 15 so that the seats may be swung around at will to face the direction of movement of the car.

As shown in Figure 2, car 10 may not be provided with a baggage rack, and in such case I install my fixture 14 in the roof or ceiling 10a of the car.

20 In each case, however, as shown in Figures 1 and 2 the beams of light as indicated by arrows A emanating from fixture 14 encompass transversely the seats 12 located therebelow. Light from fixtures 14 illuminates the normal reading plane of the passengers. This plane, indicated at P in Figure 3, is approximately at an angle of 45° with respect to the horizontal, with its center located preferably about 33 inches from the floor. As will be more clearly pointed out hereinbelow, 30 lighting fixture 14 also diffuses light in lateral directions, as indicated by arrows B, this diffusion, however, being of relatively low intensity.

Referring now to Figure 3, it may be seen that the beam of light rays A viewed transversely 35 encompasses seat 12 and reading plane P longitudinally. As is better shown in Figure 4, the light beam A is asymmetrical in shape, and thus conforms generally to the shape of seats 12, but there is no overlapping of adjacent beams, which 40 might result in areas of intense illumination, productive of glare. Referring back to Figure 3, it may also be seen that low intensity beams B emanate longitudinally from lighting fixtures 14, so as to illuminate softly the areas between the 45 high intensity beams and thus produce a general atmosphere of warmth throughout the car, and particularly in the ceiling thereof.

Referring now to Figure 5, illuminator 14 is shown in its installed position in either the baggage rack or car ceiling, preferably baggage rack 13. Baggage rack 13 has a hole 16 formed therein, through which extends a reflector 17 attached to a frame 18 or the like, suitably secured to rack 13 as by welding for example, frame 18 bordering 55

hole 16. A bracket 19 is screwed to a portion of reflector 17, and this bracket mounts a bulb and socket 20, which extends through hole 17a in the reflector, so as to position the electric light bulb 5 therewithin.

A hinge 21 is screwed to a depending portion 17b of the reflector, and carries a flanged frame 22, which is enabled accordingly to pivot relative to the reflector and baggage rack 13 about the 10 axis of hinge 21. Frame 22, as viewed in the left-hand portion of Figure 5, has an extension 22a which is provided with a slot 23. Slot 23 receives a screw 24, which extends into a U-shaped bracket 25 pivotally connected to a pair of lugs 15 26 secured to and extending from reflector 17. A spring 27 encircles the upper end of screw 24 and bears against the bottom of U-shaped bracket 25, and against a washer and cotter pin 28 associated with the end of screw 24, the screw 20 thus being urged in an upward direction to force the head thereof against frame portion 22a to hold the frame in closed position in relation to baggage rack 13. By swinging screw 24 to the left about the pivotal axis of U-shaped bracket 25, frame 22 may be swung open to permit access to the interior of reflector 17, and also to permit installation of a lens generally indicated at 29.

Lens 29 is in the general form of a rectangular flanged dish. Interposed between the flanges 30 22b of frame 22 and the flanges of lens 29, I provide a suitable gasket or the like 30 which cushions the seat of lens 29 in the frame and prevents breakage thereof from vibration. The lens is held in its installed position preferably 35 by a suitable clamp 31 or the like, which is secured to frame 22 and bears against the lens flanges.

With reference to Figure 6, wherein there is shown an exploded perspective view of lens 29, the lens generally comprises an inner portion 40 generally indicated at 32 and an outer portion generally indicated at 33, between the vertical sides of which are disposed light filters 34, all as will be more fully described hereinafter.

Upper lens 32 has a lower portion 35, on the bottom of which are formed concentric circular corrugations or prisms 37, these prisms being divided into four quadrants, as indicated by lines a, b, c and d. These prisms are so formed as 45 to gather and concentrate light beams emanating from light bulb 20. Extending upwardly from bottom 35 are side walls 38 which terminate in a spacing flange 39 lying directly below a supporting flange 40. Under certain circumstances 50 the exterior surfaces of side walls 38 may be etched as by hydrofluoric acid, the etching being provided, or not provided, in accordance with the intensity of light diffusion desired.

Lower lens portion 33 comprises a bottom 41 60 having formed on the upper surface thereof, as viewed in Figure 6, parallel corrugations or prisms 42. Extending upwardly from bottom 41 are side walls 43 on the inner surface of which are formed parallel corrugations or prisms 44, and bordering and extending from the top of side walls 43 is a supporting flange 45 which as is 65 better shown in Figure 5 rests on gasket 30 when lens 29 is installed in frame 22.

Still referring to Figure 5 it may now be seen 70 that when lens parts 32 and 33 are assembled and are installed in frame 22, flange 45 of lower lens part 33 is supported by frame flange 22b and gasket 30 and supports flange 40 of upper lens part 32. Spacing flange 39 of the upper 75 lens part spaces side walls 38 and 43 respectively

of the lens parts, these side walls also preferably being so proportioned that a space 46 is provided between bottoms 35 and 41 of the lens parts. It should be noted that prisms 44 on the side walls of lower lens part 33 lie within the 5 space between the adjacent lens part side walls, while prisms 37 on the bottom of the upper lens part and prisms 42 on the lower lens part extend into space 46 between these two parts.

Still referring to Figure 5, in the space between 10 side walls 38 and 43 of lens parts 32 and 33 respectively, I dispose filter strips 34, these filter strips preferably being formed from cellulose acetate or other suitable material having heat resistant qualities, and also being variable as to 15 thickness and size according to the intensity of light diffusion desired.

Preferably flanges 40 and 45 of the upper and lower lens parts 32 and 33 respectively are cemented together at their contiguous surfaces to 20 hermetically seal the space between the lens parts, effectively precluding the entrance of dust or moisture, which otherwise might lodge between the prisms and on the etched surface of the upper lens part side walls 38, and detract from 25 the efficiency of the lens.

While I prefer to form my lens 29 as hereinabove described, under certain circumstances the filters 34 between the lens side walls may be dispensed with. However, where the filter and 30 etched side walls are combined with the prisms on side walls 43 of lower lens part 33, the emanation of light, that is, the production of low intensity beams B (see Figures 1, 2 and 3) is soft but yet ample for general illumination outside of 35 the high intensity areas of illumination. It should also be noted that pleasing effects can be produced by using colored filters 34.

It will now appear that the horizontal lens bottoms 35 and 41 of lens parts 32 and 33 form 40 a double prismatic lens; lens bottom 35 is a concentrating or collecting lens, and lens bottom 41 is a diffusing lens. For a detailed description of such a lens, reference is made to United States Letters Patent to William A. Dorey 1,740,229 45 and 1,674,164. By utilizing a double prismatic lens of this type it is possible to produce an asymmetric beam rather than a symmetrical beam, and accordingly further localize the illuminated area, or conform the beam in shape to the general shape of the area to be illuminated as for example a pair of seats in a railroad car. As has been noted hereinabove, such lenses are useful in and of themselves under certain circumstances, but it is much more desirable to have a 55 soft diffusion of light outside of the brilliantly illuminated areas, and this is effected conveniently by lens side walls 38 and 43, which will hereinafter be referred to as "light spills."

Referring now to Figures 7 and 8 which show 60 a modified form of my light fixture or lens, the lens generally indicated at 47 in Figure 7 includes a semi-cylindrical or trough-shaped double prismatic lens 48, formed by upper and lower portions 49 and 50 (Figure 8) having on their 65 adjacent surfaces prisms 51 and 52; prisms 51 are concentric circles divided into quadrants while prisms 52 are substantially parallel. Consequently portion 49 acts in a collecting capacity and portion 50 in a diffusing capacity. Lens 70 75 47 is also provided at its ends with substantially vertical light spills 53 and 54 comprising inner and outer parts 55 and 56 (Figure 8) having interposed therebetween light filters 57 preferably having light diffusing characteristics similar to 75

filters 34 (Figure 6). Similarly an etched surface may be provided on inner wall 55 if desired.

Lens 47, as in the case of lens 29, is provided with a suitable flange generally indicated at 58 for purposes of installation. Thus lens 47 will diffuse light of high intensity substantially in planes perpendicular to the axis of semi-cylindrical double prismatic lens 48, but will diffuse light of low intensity in planes substantially parallel to this axis, thus producing a generally fan-shaped area of intense illumination and a generally horizontal area of low-intensity light.

In Figures 9 and 10 I have shown still another modification of my lighting fixture. In Figure 9 a lens generally indicated at 59 is generally semi-hexagonal in form, comprising double prismatic lenses 55, 76 and 57 with light spills 78 and 79 at the opposite ends thereof, the whole being provided with a supporting flange 60. Double prismatic lenses 55, 76 and 57 are substantially similar to the double prismatic lenses heretofore described, the same being true of light spills 78 and 79. For example, double prismatic lens 78 comprises an upper part 61 and a lower part 62. Concentric prisms 63 are formed on the bottom surface of upper lens part 61, while the upper surface of lower lens part 62 is provided with parallel prisms 64. Thus light is concentrated by upper lens part 61 and diffused by lower lens part 62.

As pointed out above, light spills 78 and 79 are substantially similar to light spills 38 and 43, thus light spill 78 is formed by inner and outer end walls 65 and 66 between which is disposed a light filter 67 substantially similar to light filters 34 (Figure 6). Preferably a plurality of vertical parallel prisms 68 (Figure 10) are formed on the inner surface of outer wall 66 and the outer surface of inner wall 65 may be etched if desired. Under certain circumstances I have found it desirable to substitute a light spill in the place of double prismatic lens 76.

As has been stated hereinabove, it is readily possible to control the intensity of light diffusion from any of the light spills described merely by using light filters of different thickness. It can readily be seen therefore that this feature is of substantial importance in that it permits of high production manufacture of standard individual lenses, the low intensity diffusion of which is controlled by the use of filters of desired density.

Accordingly I have provided a lighting fixture particularly well suited to accomplish efficiently the various purposes and objects hereinbefore stated.

As many possible embodiments may be made of the above invention and as many changes might be made in the embodiment above set forth, it is to be understood that all matter hereinbefore set forth, or shown in the accompanying drawings, is to be interpreted as illustrative and not in a limiting sense.

I claim:

1. In a lighting fixture construction of the type used upon railway cars to produce rays of light of controlled intensity and direction whereby a strong beam of light is directed toward an area where an object is to be illuminated and light of less intensity is directed toward other areas, a dish-like lens construction to be positioned in front of a source of concentrated light and held in place by a rectangular frame structure, said lens construction comprising a first dish-like

member rigidly positioned within a second dish-like member and a translucent filter strip adapted to pass only a predetermined light, each of said dish-like members being provided with a peripheral rim portion and central and side wall portions, and said dish-like members contacting each other at their rim portions but being spaced from each other at their central and side wall portions, said filter strip being a separate band positioned between said dish-like members along said side wall portions, the central portion of one of said dish-like members being provided with a plurality of concentric light concentrating corrugations and the central portion of the other of said dish-like elements being provided with a plurality of parallel light diffusing corrugations, and the side wall portions of one of said dish-like elements being frosted.

2. In a lighting fixture construction of the type used upon railway cars to produce rays of light of controlled intensity and direction whereby a strong beam of light is directed toward an area where an object is to be illuminated and light of less intensity is directed toward other areas, a dish-like lens construction to be positioned in front of a source of concentrated light and held in place by a rectangular frame structure, said lens construction comprising a first dish-like member rigidly positioned within a second dish-like member and a plurality of translucent filter strips adapted to pass only light of a predetermined range of wave lengths, each of said dish-like members being rectangular and being provided with a peripheral rim portion and central and side wall portions, said side wall portions extending on all sides between said rim portion and said central wall portion, and said dish-like members contacting each other at their rim portions but being spaced from each other at their central and side wall portions, said filter strips being positioned end to end between said dish-like members along said side wall portions, the central portion of one of said dish-like members being provided with a plurality of concentric light-concentrating corrugations and the central portion of the other of said dish-like elements being provided with a plurality of parallel light-diffusing corrugations, and the side wall portions of one of said dish-like elements being frosted.

3. In a lighting fixture for a railway car, a source of light, a lens construction positioned in front of said source of light, and bracket means supporting said lens construction, said lens construction comprising a first dish-like member and a second dish-like member with translucent filter strips along the sides thereof, said second dish-like member being nested within said first dish-like member and said dish-like members having substantially coextensive bottom and side walls and integral peripheral rim portions, said rim portions being held rigidly in contact with each other to maintain said bottom and side walls in definite spaced relationship, said filter strips comprising thin translucent members positioned between the side walls of said first dish-like member and the coextending side walls of said second dish-like member.

4. In a railway-car lighting fixture having a concentrated source of light, a lens construction comprising two dish-like members and a translucent filter-strip means, each of said dish-like members being provided with a peripheral rim portion and central and side wall portions, said peripheral rim portions being clamped in posi-

- tion and thereby providing a rigid support holding the respective walls of said dish-like members in predetermined spaced relationship, said filter-strip means extending between said spaced wall portions, said central and side wall portions of said dish-like members being respectively co-extensive and there being light-directing prisms at the central portion of said lens and a frosted surface on said side wall portions of one of said dish-like members coextensive with said filter-strip means—whereby the light which passes through said bottom wall is diffused in an asymmetrical beam and the light of low intensity passes from said side walls.
5. A lens construction as claimed in claim 4 wherein the central portions of said dish-like members are in the form of flat plates which are positioned in parallel spaced relationship and wherein the adjacent surfaces of said flat plates

are provided with prisms with the prisms on one plate being in the form of parallel transverse corrugations and with the prisms on the other plate in the form of concentric circular corrugations.

6. A lens construction as claimed in claim 4 wherein the central portion of each of said dish-like members is in the form of a semi-cylindrical portion and said side wall portions are in the form of disc segments covering the ends of said 10 semi-cylindrical portions.

7. A lens construction as claimed in claim 4 wherein the central portion of each of said dish-like members is in the form of a semi-hexagonal portion and said side wall portions are in the 15 form of plate segments covering the ends of said semi-hexagonal portions.

LINDSLEY SCHEPMOES.
